US0D1079782S

(12) **United States Design Patent** (10) **Patent No.:** **US D1,079,782 S**
(45) **Date of Patent:** **** Jun. 17, 2025**

(54) **CAMERA**

(71) Applicant: **Amazon Technologies, Inc.**, Seattle, WA (US)

(72) Inventors: **Victoria Hunt**, Amherst, NH (US); **Justin Brousseau**, Brighton, MA (US); **Jonathan E. Cohn**, Acton, MA (US); **Paul Douglas Grearson**, Salisbury, MA (US); **Michael James O'Connor**, Charlestown, MA (US); **Marcus Townsend**, San Francisco, CA (US); **Jon Varteresian**, Hubbardston, MA (US)

(73) Assignee: **Amazon Technologies, Inc.**, Seattle, WA (US)

(**) Term: **15 Years**

(21) Appl. No.: **29/911,942**

(22) Filed: **Sep. 11, 2023**

(51) **LOC (15) Cl.** **16-01**

(52) **U.S. Cl.**

USPC **D16/202**

(58) **Field of Classification Search**
